W. E. WARD

BURGLARPROOF SASH FASTENER

Filed Oct. 6, 1926

INVENTOR.
WILLIAM E. WARD.
BY.
H. A. Dreckman
ATTORNEY.

UNITED STATES PATENT OFFICE.

WILLIAM E. WARD, OF LONG BEACH, CALIFORNIA.

BURGLARPROOF SASH FASTENER.

Application filed October 6, 1926. Serial No. 139,825.

An object of my invention is to provide a sash fastener which will effectively secure the windows against further opening in any desired position.

5 Another object is to provide a sash fastener which may be readily released or engaged as desired, and with a minimum of effort.

A still further object is to provide a sash fastener which is simple in construction, inexpensive to manufacture and highly effective in operation.

10 Other objects, advantages and features of invention may appear from the accompanying drawing, subjoined detailed description 15 and the appended claims.

In the drawing—

Fig. 1 is a fragmentary, longitudinal, sectional view of a pair of window sashes with my fastener in position, thereon.

20 Fig. 2 is a side elevation of my fastener.

Fig. 3 is a plan view of the same.

Referring more particularly to the drawing:

The numeral 1 indicates the upper window 25 sash and 2 the lower sash. A plate 3 is secured to the top of the sash 2 adjacent the side thereof, the said plate being secured to the sash by a plurality of screws 4, or the like. A wedge member 5 is mounted on the 30 plate 3 and comprises an inclined wedge face 6, said face being adjacent the upper sash 1 and is inclined away from said sash.

The member 5 may be formed either as a casting integral with the plate 3, or a single 35 strip of metal may be bent to form the inclined wedge 6 and may then be bent downwardly as at 7, and may be suitably secured to the plate 3 by rivets 8, or similar fastening.

40 A roller 9 is journaled between a pair of links 10, 10 and a pin 11 extends through the links 10 at the end opposite the roller 9. The pin 11 being positioned inside of the

wedge member 5 so that the roller 9 is movably mounted thereon. In operation the 45 windows are moved to any desired position either open or closed and the roller 9 is then moved to the position shown in Fig. 1; that is, it is wedged between the sash 1 and the inclined wedge 6. Thus it will be seen that 50 an attempted upward movement of the sash 2 or a downward movement of the sash 1, will only serve to wedge the roller 9 more firmly between the sash 1 and inclined wedge 6; thus securely holding the sashes 1, 2 against 55 relative movement. The wedging of the roller 9 between the window and the member 5 serves to force the sashes 1, 2 apart, and thus further aids in preventing relative movement of the window by binding the sashes 60 against their guides.

To prevent accidental displacement of the roller 9 when it is in fastening position, a stop lug 12 is provided on the inside of the wedge member 6 against which the pin 11 65 rests; thus preventing an upward movement of the roller 9, links 10 and pin 11. When it is desired to release the windows the roller 9 is lifted upwardly and swung to the position shown in Figures 2 and 3, at which time 70 the windows are free to move.

Having described my invention, I claim:

In a window comprising upper and lower sashes, a plate secured to the top of the lower sash, a wedge member secured to said plate, 75 said wedge member comprising an inclined wedge plate, a roller, links on which said roller is journaled, a pin extending between said links and back of said wedge plate, said links serving to couple the roller to the 80 wedge member, a stop lug on the inside of said inclined wedge plate, against which said pin is adapted to rest to prevent accidental displacement of the roller.

In testimony, whereof, I affix my signature.

WILLIAM E. WARD.
